UNITED STATES PATENT OFFICE.

WILLIAM GORDON, OF NEW YORK, N. Y.

DESIGN FOR A TOBACCO-ASH RECEIVER.

Application filed June 9, 1928. Serial No. 27,066. Term of patent 7 years.

To all whom it may concern:

Be it known that I, WILLIAM GORDON, a citizen of the United States, residing at the borough of Manhattan, in the city, county, and State of New York, have invented a new, original, and ornamental Design for Tobacco-Ash Receivers, of which the following is a specification, reference being had to the accompanying drawing, forming part thereof.

The figure is a perspective view of a tobacco-ash receiver, showing my new design. The essence of the design consists of the tobacco ash receiver of conoidal contour, as shown.

I claim:

The ornamental design for a tobacco ash receiver, as shown and described.

WILLIAM GORDON.
